UNITED STATES PATENT OFFICE.

THOMAS SPENCER MILLER, OF SOUTH ORANGE, NEW JERSEY.

CONVEYING APPARATUS.

SPECIFICATION forming part of Letters Patent No. 637,143, dated November 14, 1899.

Application filed December 31, 1898. Serial No. 700,836. (No model.)

To all whom it may concern:

Be it known that I, THOMAS SPENCER MILLER, a citizen of the United States, and a resident of South Orange, in the county of Essex and State of New Jersey, have invented certain new and useful Improvements in Conveying Apparatus, of which the following is a specification.

The primary object of my invention is to provide for the conveyance of coal or other commodities between boats at sea.

In the accompanying drawings I have shown the best mode in which I have thus far contemplated applying the principle of my invention, which, however, may be applied in various other forms.

Figure 1 is a side view of two ships equipped with an apparatus according to my invention. Fig. 2 is a detail of the same enlarged. Fig. 3 is a side view of the load-carriage. Fig. 4 is a longitudinal section of the same. Fig. 5 is a side view of the forward and backward actuators and mechanism for operating the same. Fig. 6 is a plan view of the same with one of the actuators in section.

A is a ship to which coal, provisions, mail, or other commodity is to be delivered from the ship B. C is a rope connecting the two ships. The ship A is provided with propelling mechanism, so that while the apparatus is in operation the propelling mechanism on the ship A causes it to pull the ship B through the pull-line C. If, as is preferable, the ship B is not anchored, this pulling action will tow the boat B along, but otherwise if the ship B is at anchor. In either case, however, the propelling of the ship A in a direction away from the ship B, to which it is attached by the pull-line C, will serve to maintain as uniform a distance between the ships as the elements will permit.

D is a load-support, from which the load is suspended while in transit. In the particular form of load-support shown in the drawings it is a carriage provided with wheels that run upon a rope across the span.

E is a transit-rope extending from an elevated support F on one boat to an elevated support G on the other. If the transit-motor hereinafter described is wholly located off of the ship A, as I prefer and as hereinafter particularly described, the transit-rope E will

consist of two branches, one of which, e' , extends from the elevated support on ship B to and around a sheave g on the elevated support of ship A, and the other of which, e^2 , extends thence back to the elevated support on ship B. The two branches e' and e^2 are preferably substantially parallel. The transit-rope E is fastened to the load-support D in some manner suitable for moving the load-support. The method of fastening I prefer is by such a gripping engagement as is indicated in Fig. 4, where the upper branch e^2 of the transit-rope is gripped between the block d' , fixed between the side plates d^2 d^3 of the load-support, and the block d^4 . A yoke d^5 causes the blocks d' and d^4 to clamp between them the transit-rope with any desired degree of firmness necessary for traction and yet with sufficient lack of firmness to permit the transit-rope to slip through the load-carriage, and thus prevent breakage if the load-carriage happens to strike an obstruction.

d^6 and d^7 are wheels journaled in the side frames d^2 and d^3 and which enable the load-support to run as a carriage upon a rope crossing the span—as, for example, upon the lower branch e' of the transit-rope itself.

H is a transit-motor by which motion is imparted to the transit-rope. Preferably, though not necessarily, it consists of two transit-actuators—an outward transit-actuator and an inward transit-actuator—engaging, respectively, with different parts of the transit-rope and each independently controllable as to power. Preferably, also, though not necessarily, they are driven by a common prime-mover actuator, by controlling the speed of which the transit-actuators may be further controlled as to speed of motion. Preferably also, though not necessarily, the actuating power is produced by the pressure of a fluid, such as steam, water, or gas. The preferable form of constructing such actuators and prime mover may be described as follows:

h' is the forward actuator, which consists of a friction-rope drum that may be constructed, operated, and frictionally controlled substantially as shown in United States Patent No. 541,308, dated June 18, 1895. h^2 is the backward actuator, which may consist of a rope-drum similarly constructed, operated, and frictionally controlled. Gear-wheels of

both rope-drums are driven by a shaft h^3 , which is driven by a suitable motor, such as the power of steam or other fluid in the engine-cylinder h^4 . The attendant may start, 5 stop, and control the speed of the motor and thereby of the two actuators h' and h^2 jointly. He may also control the power of each actuator independently by means of its friction connection with its motor. Opposite ends of 10 the transit-rope E are connected with the drums h' and h^2 , respectively, in such manner that in operation said drums tend to pull on the transit-rope antagonistically. When pulling against each other with equal power, 15 both drums may remain at rest by the slipping of both their frictions. When the operator adjusts the frictions so that the power of one exceeds that of the other, the transit-rope will be hauled in by the most powerful 20 actuator, while the least powerful actuator will act as a tension device, as it is compelled to pay out the transit-rope. Either or both actuators are ready to quickly take in any slack of the transit-rope that may be caused 25 by the lurching of the boats toward each other or to give out any additional length of transit-rope required by the lurching of the boats away from each other during the transit operation. During the forward transit, with the 30 load I suspended from the load-support, greater friction will be applied to the forward actuator h' than to the backward actuator h^2 ; but sufficient friction will be applied to the backward actuator h^2 to cause it to supply 35 sufficient tension for holding the load at a proper normal elevation in crossing the span. During the backward transit of the unloaded load-support less friction will be applied to the forward transit-actuator h' than to the 40 backward transit-actuator h^2 , and the friction on the forward transit-actuator h' may be lightened, so as to reduce the tension which it exerts upon the transit-rope to a minimum and even to the extent of permitting the 45 transit-rope to sag and rest in the water, if desired. Therefore, if desired, the tension strain upon the parts of the apparatus and between the two boats necessary for maintaining the load at a normal elevation may be 50 exerted only while the load is actually in transit.

A desirable form of mechanism for actuating and controlling the forward and backward actuators is shown in Figs. 5 and 6, 55 which may be described as follows: The fluid-pressure in the cylinders h^4 drives the shaft h^3 , which drives the gear-wheel h^5 , fixed to the drum-shaft h^6 , and the gear-wheel h^7 , fixed to the drum-shaft h^8 . Both of the drum-shafts h^6 and h^8 are therefore continuously 60 driven in the same direction at the same speed, so that they tend to drive the drums h' and h^2 in such direction as to tend to cause both drums to either haul in or pay out at 65 the same time. The drum h' is loose on the shaft h^6 , but by any well-known mechanism may be shoved toward the spur-wheel h^5 , so

as to press the friction-surfaces h^9 and h^{10} together with a power within the control of the operator at the lever h^{11} . The drum h^2 70 runs loose on the shaft h^8 and the sleeve h^{12} , which is splined to the shaft. At one end the drum h^2 is provided with a disk friction-surface h^{13} , which coöperates with the disk friction-surface h^{14} , fixed to the spur-wheel 75 h^7 . At the opposite end the drum h^2 is provided with a disk friction-surface h^{15} , which coöperates with a disk friction-surface h^{16} , fixed to arms h^{17} , projecting from the sleeve h^{12} . h^{18} is a gib operated in a well-known 80 manner from the hand-lever h^{19} . Between the gib h^{18} and the end of the sleeve h^{12} is the coil-spring h^{20} . The spring h^{20} is interposed in the train of mechanism between the lever h^{19} and the friction-surfaces by which 85 the drum h^2 is driven. The power of said spring will determine and maintain with reasonable constancy the tension of the drum h^2 upon the rope branch e^2 . When therefore the lever h^{19} is set so as to compress the spring 90 h^{20} , the friction-surfaces of the drum h^2 will slip and the drum will pay out as long as the pull of the rope branch e^2 against it exceeds its tension, as may be the case when the vessels lurch away from each other or when the 95 operator has forced the friction-surfaces of drum h' together so that their tension exceeds the tension of the friction-surfaces at the drum h^2 . On the other hand, whenever the pull on the rope branch e^2 is less than the 100 tension of the drum h^2 that drum will haul in, as may be the case when the vessels lurch suddenly toward each other or the operator eases up on the friction-surfaces at the drum h' . The operator, therefore, may set the lever 105 h^{19} so as to produce an amount of compression of the spring h^{20} equivalent to the tension that he desires the drum h^2 to operate under and may leave the lever h^{19} so set and may then 110 give his entire attention to the lever h^{11} , by 115 the operation of which he may increase the power of the forward-actuating drum h' above or may reduce it below the tension of the backward-actuating drum h^2 . I have shown the drum h' as of larger diameter than the 120 drum h^2 , which produces a differential action that I prefer because it tends to act with greater quickness upon the rope.

The support F may be provided with sheaves f' and f^2 , over which, respectively, the branches 120 of the transit-rope E may extend down to the transit-motor H, if the same be mounted upon the deck of the ship B. The block of sheave g may be provided with an abutment g' , against which apparatus mounted upon the 125 carriage may strike, so as to automatically detach the load from its support and allow it to drop it onto an inclined apron J, down which it may slide to the deck of the ship A. The 130 loads may be elevated from the deck of the ship B to the level of the load-support D in an elevator-box K, running on guides k , and hoisted by a rope k' and drum k^2 or by any other suitable means.

When a load is presented at the level of the load-support, it is desirable that the load-support should be capable of picking it up automatically, and for that purpose the following mechanism is provided: Each load is provided with a bail i , which as the load-support approaches the end of its backward transit is held in line to receive a hook l , pivoted to the carriage-frame at l' . This hook is shown in Fig. 4 in its supporting position and in Fig. 3 in its discharging position. In its supporting position it is held by a latch l^2 , pressed by the spring l^3 . When the hook l has once passed into the bail i , as shown in Fig. 4, it is prevented from accidentally escaping while the hook is in supporting position by the guard l^4 , which is held by the spring l^5 against the pins l^6 and l^7 . The hook is so balanced on the pivot l' that it returns itself to the supporting position against the pin l^8 whenever unloaded, but the weight of the load is sufficient to swing it downward whenever released by the latch l^2 . This release is accomplished by the striking of the latch against the abutment g' , as shown in Fig. 3. Pendent from the lower part of the carriage is a weight l^9 , which serves to prevent the upsetting of the carriage and the winding of the transit-rope members e' and e^2 around themselves when the load is dropped.

In order that the apparatus may meet the varying conditions due to the lurching of the ships with the greatest certainty and quickness, I construct and operate the outward transit-actuator so as to run at a speed adapted to actuate the transit-rope at a speed greater than the relative motion between said boats due to the waves. The maximum speed at which the distance between supports upon the two ships may be expected to decrease from waves or other causes may be taken as five feet per second. The forward transit-drum will be speeded so as to haul in the transit-rope at a rate in excess of ten feet per second—say, for example, at the rate of fifteen feet per second. Now suppose during the transit of a load that the ships lurch toward each other at the maximum rate of five feet per second. Since there are two lengths of the rope E stretched between the ships, this will produce a slack in the rope at the rate of ten feet per second; but the rate at which this slack is produced is less than the fifteen-feet-per-second speed of the forward transit-drum, and consequently the forward transit-drum takes up this slack as fast as produced, with five-feet-per-second speed to spare, and the normal elevation of the load is maintained. Suppose now that the ships lurch away from each other. This will demand a greater length of rope on the span, which will be supplied by the backward transit-drum (which for the time being is acting as the tension-drum) by causing it to pay out at a speed accelerated to any extent demanded. Therefore it will be seen that under all possible conditions the apparatus will maintain the load at substantially a normal

elevation and relieve itself automatically from undue strain.

The construction above described is the present culmination and embodiment of a series of inventions represented in forms of apparatus differing more or less from that above described, but each of itself embodying more or less of the principles of that above described, and each of itself being, therefore, more or less adapted for success. Therefore I do not wish to be understood as limiting myself to any single principle involved in the foregoing apparatus or to forms of construction. Among other things I do not limit myself in certain claims to the division of the transit-actuator into two parts, (a forward and backward actuator.) If divided into two parts, I do not limit myself to locating both of them on the same ship, nor to driving both of them by the same motor, nor to the employment of any part of the transit-actuator as the tension device, nor to the location of the tension device on either of the ships; nor do I limit myself to having the transit-rope either continuous or non-continuous, nor to its extending a plurality of times across the span, nor to the engagement of the load-carrier with both branches thereof, nor to the actuation of the load-carrier both forward and backward by the same branch of the transit-rope, nor to the absence of a supporting-cable in addition to the transit-rope; nor do I limit myself to the production of the pulling action by the receiving-boat or by any particular source of power.

I claim—

1. In combination, a pulling-boat, a pulled boat, a pull-rope, a transit-rope, a load-support moved thereby, an actuator of said transit-rope and a tension device acting upon said transit-rope, substantially as described.

2. In combination, a pulling-boat, a pulled boat, a pull-rope, a transit-rope, a load-support supported and moved thereby, an actuator of said transit-rope and a tension device acting upon said transit-rope, substantially as described.

3. In combination, a pulling-boat, a pulled boat, a pull-rope, a transit-rope, a load-support moved thereby, an actuator of said transit-rope and a tension device by which and said actuator the transit-rope is held taut, substantially as described.

4. In combination, a pulling-boat, a pulled boat, a pull-rope, a transit-rope, a load-support moved thereby, an actuator of said transit-rope, a tension device by which and said actuator the transit-rope is held taut and means whereby the power exerted upon said transit-rope by said actuator may be made to exceed the power exerted by said tension device, substantially as described.

5. In combination, a pulling-boat, a pulled boat, a pull-rope, a transit-rope, a load-support moved thereby, an actuator of said transit-rope, a tension device by which and said actuator the transit-rope is held taut and means

- whereby said actuator is driven at a speed of actuation exceeding the speed of relative motion between said boats due to the waves, substantially as described.
- 5 6. In combination, a pulling-boat, a pulled boat, a pull-rope, a transit-rope extending from one boat to the other and back again, a load-support moved by said transit-rope, an actuator of said transit-rope and a tension device acting upon said transit-rope, substantially as described.
- 10 7. In combination, a pulling-boat, a pulled boat, a pull-rope, a transit-rope extending from one boat to the other and back again, a load-carriage running upon one branch of said transit-rope and moved by the other branch thereof, an actuator of said transit-rope and a tension device acting upon said transit-rope, substantially as described.
- 15 8. In combination, a pulling-boat, a pulled boat, a pull-rope, a transit-rope, a load-support moved thereby, a tension device acting upon said transit-rope, a rope-drum whereby said transit-rope is actuated and a friction-clutch whereby the movement of said rope-drum is controlled, substantially as described.
- 20 9. In combination, a pulling-boat, a pulled boat, a pull-rope, a transit-rope, a load-support moved thereby, a rope-drum connected with each end of said transit-rope and friction-clutches whereby the power of said rope-drums, respectively, is controlled, substantially as described.
- 25 10. In combination, a pulling-boat, a pulled boat, a pull-rope, a transit-rope, a load-support moved thereby, a rope-drum connected with each end of said transit-rope, and friction-clutches whereby the power of said rope-drums, respectively, is controlled and a common prime mover whereby said friction-drums are actuated, substantially as described.
- 30 11. In combination, a pulled boat, a pulling-boat, a pull-rope, a transit-rope, a load-support moved by said transit-rope, a forward transit-actuator and a backward transit-actuator, substantially as described.
- 35 12. In combination, a pulled boat, a pulling-boat, a pull-rope, a transit-rope, a load-support moved by said transit-rope, a forward transit-actuator, a backward transit-actuator, means whereby the power of the forward transit-actuator may be reduced below
- the power of the backward transit-actuator, substantially as described.
- 40 13. In combination, a pulled boat, a pulling-boat, a pull-rope, a load-carrier, a rope supporting the same, between the boats and means for maintaining a normal elevation of said carrier during its transit consisting of a tension device in which a fluid supported independently of the strain on said supporting-rope is caused to flow by said strain; substantially as described.
- 45 14. In combination, a pulling-boat, a pulled boat, a pull-rope, a load-carrier, a transit-rope, a load-carrier moved thereby and means for maintaining a normal elevation of said transit-rope during transit, consisting of a tension device in which the pressure of a fluid is opposed to the strain of said transit-rope; substantially as described.
- 50 15. In combination, two relatively-moving supports, a transit-rope extending between the same, a forward transit-actuator and a backward transit-actuator acting upon said rope antagonistically, the power applied to said backward transit-actuator being adapted to yield to the power of the forward transit-actuator and thereby pay out the transit-rope under tension, substantially as described.
- 55 16. In combination, two relatively-moving supports, a transit-rope extending between the same, a forward transit-actuator and a backward transit-actuator operating upon said rope antagonistically, the power applied to both of said transit-actuators being adapted to yield, substantially as described.
- 60 17. In combination, two relatively-moving supports, a transit-rope extending from one support to the other and back again, a load-carrier having a yielding traction engagement with said rope and a transit-actuator, substantially as described.
- 65 18. In combination, two relatively-moving supports, a transit-rope extending from one support to the other and back again, a load-carriage having a yielding traction engagement with one branch of said rope and a running engagement with the other branch thereof and a transit-rope actuator, substantially as described.
